The ornamental design for an infrared digital transceiver, as shown and described.

DESCRIPTION

FIG. 1 is a top plan view of an infrared digital transceiver showing our new design, the bottom being unornamented;

FIG. 2 is a left side elevation view thereof;

FIG. 3 is a right side elevation view thereof;

FIG. 4 is a front elevation view thereof, the rear surface following the configuration shown in FIG. 1-3;

FIG. 5 is a top plan view of the second embodiment of the design of FIG. 1 the only difference being the inclusion of a stand on the rear, and;

FIG. 6 is a left side elevation view of FIG. 5 the bottom surface of the stand following the configuration shown on its side; and,

FIG. 7 is a perspective view of FIG. 5, the broken line showing of the cord junction being for illustrative purposes only.

FIG. 2
